UNITED STATES PATENT OFFICE

EUGENE SCHMIDT, OF ST. PAUL, MINNESOTA

AIRPLANE

Application filed April 25, 1928. Serial No. 272,713.

My invention relates to new and useful propelling means and their application to air-ships the said term air-ship designating either heavier-than-air craft or buoyant ships 5 known as dirigibles or similar air-craft. The main object of the invention is to provide new and novel propelling means of simple and efficient construction and embodying certain features and advantages hereinafter 10 fully set forth and as illustrated in the accompanying drawings in which,—

Fig. 1 is a top view of an air plane of the so-called monoplane type with my improved propelling means, only the right hand half 15 of the plane wing being shown to more clearly expose the left side propeller.

Fig. 2 is a left side elevation of Fig. 1.

Fig. 3 is a longitudinal vertical section of the plane body as at line 3—3 in Fig. 1 and 20 showing a modified mounting of the propelling means.

Fig. 4 is a front elevation of Figs. 1 or 2.

Fig. 5 is a horizontal sectional elevation taken on a plane just above the propeller 25 wing wheels of my devices as on line 5—5 in Fig. 4.

Fig. 6 is a side elevation of a dirigible airship embodying a number of my propeller devices mounted in its cabin frame.

Referring to the drawing by reference numerals 10 designates the elongated cabin or body of an airplane, tapering rearwardly and having the usual necessary adjustable elevating and steering members 11. 12 is the supporting wheel carriage under the cabin and 30 13 represents any suitable type of ground engaging tail piece adapted to glide on the ground and support the tail end of the machine. In the cabin are illustrated a number 35 of windows 14 and a door 15. 16 is the airplane wing there being only one shown for the monoplane type although it will be readily understood that my propelling means are adaptable for biplanes, triplanes and other 40 types of air-craft, a monoplane and a dirigible aircraft only being illustrated to sufficiently illustrate my invention.

My improved device comprises a propeller and certain setting therefor in an air craft 45 the propeller being provided in number and

sizes according to the design of the air-craft, speed requirements and other governing factors. It will be observed in Figs. 1 to 5 inclusive that the body or cabin 10 may be of general shape resembling the regular torpedo shape of air-craft commonly used but I do not employ the usual type of blade propeller hitherto universally used and mounted at the front end. My propelling means consists of one or more devices which for convenience might most aptly be termed a propeller wheel 17 comprising each a series of evenly spaced radial flat blades fixed in a hub 18 with their inner ends and the outer 55 end or edge parts of all the blades being flanged angularly as at 17F in the same direction. The hub 18 is suitably fixed to a drive shaft 19 which may be an extension of the crank shaft of a motor 20 or suitably connected with such crank shaft to be rotated 60 thereby. There may be a motor for each propeller as illustrated or one motor delivering power to rotate two or more such propellers 65 (not shown) by suitable power transmission means.

In Figs. 1, 2, 4 and 5, I have illustrated a monoplane with two of my propellers one at each side of the car or body 10 and directly under the wing 16, both propellers mounted 70 to rotate in a horizontal plane and their drive shafts 19 being of course vertical and journaled above and below the propeller in a pair of horizontally and outwardly directed flat frame pieces 21 fixed rigidly to the sides 75 of the car. Forward of the shafts 19 the side frames 21 are each provided with a fixed vertical wall 22 extending outwardly far enough to cut off or deflect air from passing through the frame 21 inwardly of the shaft 19. The 80 propellers are rotated in a direction to "dig" 85 into the air forward of their shafts 19 and throw it rearwardly and outwardly of the shaft, as indicated by the arrows 23 in Figs. 90 3 and 5.

Thus it will readily be understood that the propeller blades are exposed only where the blades are working rearwardly and throwing air current in that direction to propel the 95 craft forward, the wall 22 preventing direct 100

air pressure against the blades of the propeller moving forward.

In the mounting and operation of the parts above described the propellers are outward of the body 10, but in Fig. 3 a single propeller is shown on a horizontal shaft mounted to rotate between vertical frame members 21, the shaft 19 being approximately on a common plane with the underside of the cab 10 necessitating an upward recess in the cab having a transverse front wall 22 corresponding to the wall 22 in Figs. 1, 2 and 5. From the inner and upper part of this wall 22 the recess is formed by a rearwardly extending wall or partition 24 extending past the upper part of the propeller and thence rearwardly and angularly to connect with the bottom of cab 10 as at 10C. In this view 25 designates a motor chamber in which may be mounted a suitable motor (not shown) and properly connected with shaft 19 to rotate the propeller. 26 is the cab floor. In this type of air-craft the motor is more readily accessible, but in any mounting of my device the important feature of the mounting is the transverse front wall 22 cutting off direct air pressure on the forwardly moving wings of my propeller and the sloping rearwardly extending wall 24 deflecting rearwardly any air current which may come inwardly toward the cab, and thus getting a maximum forward pushing action by the blades of the propeller moving rearwardly and outwardly of the drive shaft.

In Fig. 6 is illustrated a dirigible air-craft having the usual elongated gas bag 27 tapered toward both ends. 28 is an elongated outside frame extending from front to rear at both sides of the main bag and suitably connected with to form an integral part of the main bag frame. At predetermined locations in each side frame 28 are provided a number of my propeller devices and motors therefor as shown and between said propellers suitable passenger or freight cabins 29.

It is obvious that in the use of my propelling means for heavier-than-air ships the usual steering and level or angle attaining means hitherto in use may be also used with my device. It is further obvious that in the plane construction involved in the use of my device there are no strong rearwardly directed air currents from a point forward of the plane as in the case where the usual type of propeller is used forward of the plane cab. It may be necessary in some aircrafts embodying my invention to mount the latter to operate in angular positions but these and other variations in details of mounting and operation may be incorporated without departing from the scope and spirit of my invention, the use of which has been fully set forth in the preceding specification.

I claim:

1. An aircraft propelling device compris-

ing a number of rotatable propellers each consisting of a number of radial flat blades fixed on a hub, a drive shaft fixed in said hub and suitably connected with a source of power for rotating it, a depression formed in the air craft and frame means in which said propeller shaft is journaled, a wind-break in said frame forward of the propeller and comprising a transverse wall deflecting air currents toward the wings of said propeller outward of said propeller shaft and an inner rigid wall extending rearwardly from said front wall past said propeller and terminating in spaced relation and rearwardly of said propeller, said source of power arranged to rotate said propeller with its outer blades to move rearwardly away from said transverse wall.

2. The structure specified in claim 1 in which said aircraft comprises in part a buoyant elongated body, and further an elongated frame at each side of said body and a number of said propellers mounted in each said frame.

In testimony whereof I affix my signature. 90
EUGENE SCHMIDT.
